UNITED STATES PATENT OFFICE

FRANK G. CARRINGTON, OF ANNISTON, ALABAMA, ASSIGNOR TO FERRIC ENGINEERING COMPANY, OF ANNISTON, ALABAMA, A CORPORATION OF DELAWARE

ROTARY CASTING APPARATUS

Application filed February 24, 1927. Serial No. 170,547.

This invention relates to an apparatus for centrifugally casting pipe, and more particularly refers to a trough construction for conveying molten metal to a mold and distributing the metal therein.

Casting annular metal objects by the centrifugal, or rotary, process involves the discharge of metal in a revolving mold. The three types of molds commonly used, which necessitate different apparatus and variations in the process, are: (1) those in which the metal is poured just inside the end of the mold and the metal is distributed longitudinally by manipulation of the mold; (2) those in which the metal is poured over the side of a so-called "dump type" trough which is rotated upon its longitudinal axis and (3) those in which the metal is discharged from the end of a trough over which the mold telescopes. This invention falls into the type of machine in which the metal is deposited from the end of a trough. By avoiding the time-consuming distribution of the metal while in contact with the mold inequalities and defects in the castings are avoided and mold materials of greater heat-conductivity may be used.

Because of the relative motion of the trough with respect to the mold, and because the metal is distributed at one terminal of the trough by means of a spout attached thereto for evenly distributing the metal, the trough can be supported at one end only. This warping of the trough, both horizontally and vertically has been one of the serious problems confronting the industry. The differential heating of the trough is due to hot molten material being poured therein together with the weight of the molten material tending to cause warpage of the trough.

As the molten metal is at a very high temperature, it is necessary to line the trough. Another difficulty experienced by the industry has resided in a tendency for this lining to warp. The warpage in this instance, however, is upward, and, when occurring in conjunction with a drooping of the trough casting, there is a space between the trough and lining which makes for inaccuracy in the

amount and direction of metal discharged from the trough.

An object of this invention is to devise a method of preventing sagging of a trough supported at one end only.

Another object of this invention is a method of preventing warpage of a lining for a hot fluid conducting trough.

A further object of this invention is to provide a non-sagging trough supported at only one end.

Another object of this invention is to provide a trough with means for preventing horizontal warping of the trough.

Yet another object of this invention is to provide a spout for attachment to a liquid conveying trough.

A still further object is to provide a lining for a trough conveying hot liquids with means to prevent warpage of said lining.

With these and other important objects in view, as will more fully hereinafter appear, my invention consists in a trough apparatus comprising a casing with means for checking the expansion of the upper portion more than the lower portion, and preventing horizontal warpage of the casing, a lining mounted in said trough to permit separate expansion of the trough and lining and of such construction that there may be a relative expansion of the bottom portion independent of the top, and a spout for distributing the liquid in the mold.

In the accompanying drawings in which similar numerals indicate corresponding parts of the trough,

Figure 1 is a broken away side view of the complete trough, partly in elevation and partly in section;

Fig. 2 is a top plan view of a section of the trough with a continuous lining near its termination;

Fig. 3 is a cross sectional view of the trough and lining along the line 3—3 of Fig. 2, looking in the direction of the arrows;

Fig. 4 is a cross sectional view, similar to Fig. 3 but showing lips on the casing for retaining the lining;

Fig. 5 is a view in cross section along the

line 5—5 of Fig. 1, looking in the direction indicated by the arrows;

Fig. 6 is a longitudinal view of the casing and lining, showing an optional form of joining the sections of the lining;

Fig. 7 is a view in longitudinal section of the casing and lining showing another method of joining sections;

Fig. 8 is a front elevational view of a spout;

Fig. 9 is a top view of a portion of the trough with a modified form of lining;

Fig. 10 is a sectional view of the trough shown in Fig. 9, along the line 10—10, looking in the direction of the arrows;

Fig. 11 is a view in cross section of Fig. 9, along the line 11—11, looking in the direction of the arrows;

Fig. 12 is a cross sectional view of a trough showing an optional shape.

Referring to the accompanying drawings but in no wise limiting the scope of this invention to the particular embodiment therein set forth, there is shown in Fig. 1 a trough construction comprising a casing or support member, the shell 1 of which is partially cylindrical in cross section, and cooling means mounted in the casing. The shape of the shell may be modified as shown in Fig. 12. The cooling means set forth in Fig. 1 are

those mounted in only one side of the casing, and, as will appear in Fig. 8, similar means are provided for the other side. These means comprise a pipe 2, or other suitable channel, formed in the upper portion of the casing and extending substantially the length thereof. At the end of the pipe there is another passage 3, or bent portion of pipe 2, which connects the pipe 2 with the chamber 4 positioned below and extending to the bottom portion of the casing. It will be noted that the chamber 4 is practically co-extensive with, although of larger cross section than, the pipe. The shell extends beyond the cooling system and lining, as at 5.

The cooling medium is introduced to the casing by means of the pipe 6, and its rate of flow regulated by the valve 7 which may be a pressure regulating valve. A similar pipe and valve are provided for the cooling channel formed in the other side of the trough. An outlet pipe is connected with the chamber 4, as at 8, although it may be positioned at any point beyond the portion of the trough to be cooled. The cooling medium passes through the pipe 2, the connecting pipe 3, and then into the chamber 4 where it is finally discharged at 8. As the medium passes along this path, its temperature is increased by heat exchange with the molten metal. There will be differential temperatures of the fluid between any two points in its course and the medium will be of considerably higher temperature in the chamber 4 than in the pipe 2. This is due to the

fact that the medium in compartment 4 has been exposed to the heat of the trough and molten metal for a longer period than the medium in pipe 2, and is also a result of a more effective heat exchange between the molten metal and medium in 4 than is the case with the medium in 2.

It will therefore result that there is a less tendency for expansion of the upper portion of the trough than of the bottom. When the casing sags there is established in the upper portion a tension and in the lower portion of the casing a compression. The differentials in temperature between the upper and lower channels therefore counteract the stress set up as the casing sags.

There is also shown in Fig. 1 a conventional chute 9 into which the molten metal may be poured and which directs the metal thus received into the channel of the trough. This chute may be dispensed with if it is desired to pour the metal directly into the trough, but such a method is not advisable because the chute obviates any loss of the metal in the pouring and minimizes splashing.

The main portion of the casing terminates at 10 but there is a prolongation of the shell to 11. Into this prolongation there is fitted a spout 12, having a channel which slants downwardly as indicated by the dotted lines 13, and provided with a reduced extension for projection into the shell 5. The spout is secured in the shell by the screws 14 or other suitable means.

The chute and the spout may be considered as portions of the lining, in that they may expand independently of the trough casing. They may be formed integral with the lining or attached thereto by any of the means, described later, by which the lining sections are connected.

As shown in Fig. 2, the trough is lined with appropriate material, preferably cast iron, although certain grades of steel, such as chromium steel, may be used. The lining 15 is of the same configuration as the channel of the support member or casing, and along its length there are regularly and oppositely disposed slots 16 extending from the top of each side of the lining downwardly to a mediate point 17 of the side. The lining shown in Fig. 2 is made from one continuous strip of material, and in such case the slots may be cut out of the lining or may be made by merely sawing from the top to the point 17. As the bottom of the channel is in contact with the molten metal, it will be exposed to greater heat than the top. With this difference in temperature there will be an attendant difference in expansion of the lining, and, in the absence of some such provision as herein made, this differential expansion will cause the lining to warp upwardly. The slots herein set forth will permit the expansion of the bottom portion of

the lining independently of the upper portion, and in this way will prevent warpage. It is, of course, to be understood that these slots may be made in any suitable manner, 5 and, under certain circumstances, may be in some relation other than that here set forth—as for instance, they may be irregularly placed, or positioned in a stagger relationship, or they may slant rather than descend 10 perpendicularly. Hereafter there will be discussed certain modifications of this lining construction.

It is also to be understood that the purpose of these slots is to limit contact between relatively short sections of the lining to areas of uniform temperature. When these areas are those of the highest temperature, and therefore along the line of greatest expansion, the space between the unattached areas 20 of the liner section faces will become greater as the temperature difference over the liner increases and less as this temperature difference approaches uniformity. Should the contact areas not be located in the line of 25 greatest expansion, the unconnected portions of the liner faces which are of higher temperature than the connecting areas will decrease the slot widths as the temperature difference increases.

30 The effect of the slots may therefore be defined as permitting unrestricted lineal expansion of the lining while limiting the warping effect of temperature differentials to such short lengths that the warping in each 35 will be negligible. The positive connection between liner sections is to cause the lining to contract as a whole during periods of decreasing temperature. The drawings and above description refer largely to avoiding vertical 40 warping. Horizontal warping is prohibited by locating the contact areas so that no horizontal stresses will appear or so that the slots will compensate for them as for vertical warping. Slight horizontal stresses 45 also do not become apparent because the lining is held in line by standards of the trough.

The slot widths, are kept small to prevent the entrance of molten iron therein. Where 50 the section faces are joined by bolts or welding, Fig. 6 and Fig. 7 and described later, no slots are necessary at normal temperatures, when the bonding material is elastic or where the bond is made in the region of greatest expansion. In this case the expansion stresses 55 will be absorbed by the elastic material, or spaces will appear between the unconnected portions of the faces as the expansion differentials arise.

60 In order to allow creeping of the lining, attachment of the lining is made at only one point, or at points sufficiently close together so that the difference in expansion of the trough and the lining will not be apparent.

65 Hereafter when mention is made of attach-

ing the lining at "only one point", the term is used with this meaning. The point at which the lining is attached is preferably adjacent to the spout. There will then be no expansion toward the spout, all creeping of the lining necessarily being in the opposite direction, and consequently no tendency for the expanded lining to force the spout from contactual alignment with the trough. The lining of the casing terminates at 10, and 70 lugs, or other suitable fastening means, pass through the lining into the casing, as shown diagrammatically at 18, to anchor the lining at that point. A more secure attachment is obtained by inserting the lugs at the top 75 of the lining than at the bottom, for there is minimized the strain placed upon the fastening means.

In Fig. 3 a semi-cylindrical casing is shown. Standards 19 extend from the top 80 of the casing and converge toward the bottom, forming a channel into which the lining 15 fits. The inner faces of the standards form sides of the chamber 4. It will be observed 85 that the chambers extend considerably below the channel of the lining. Above the chamber 4 are the channels 2. Channels 2 may be formed by drilling a hole in the casing, or the casing may be formed with recesses, and plates 21 welded, brazed, or otherwise suitably secured, in the casing, which plates will 90 serve to separate the channel 2 from the channel 4. As the lower chambers are larger than chambers 2, there is a slower rate of 95 flow, which constitutes another factor in maintaining a higher temperature of the cooling medium in the lower compartments than exists in 2.

100 Horizontal warping of the trough may be prevented by regulating the temperature of the cooling medium introduced to each side of the casing, so that expansion or contraction can be offset by the variance in temperature of the cooling medium in the respective sides.

105 There is a slight bulge in the wall of the casing, as at 22, which serves to maintain the lining in position. The lining, it will be noted, because of its configuration and that of the channel of the casing into which it fits, 110 must be inserted from one end, and because of the protuberance 22, is incapable of vertical movement with respect to the casing. But as hereinbefore stated, the lining may move longitudinally of the casing in order to prevent warpage.

115 Lips may be formed on the casing, as at 23, in Fig. 4, to provide additional means for retaining the lining in the trough. These, together with the protuberances 22, serve to 120 prevent any upward warpage of the lining and limit all expansion of the lining to a horizontal plane.

125 As before stated, the spout 12 fits into the hollow shell 5 of the casing, and the cross sec-

tion of such arrangement is shown in Fig. 5. The screws 14, or other means of attachment, pass through apertures in the shell 5 and into the spout 12. The trough lining may be held in rigid contactual alignment with the spout 12 by either of the methods of joining sections of the lining depicted in Fig. 6 or 7.

Because the outside dimensions of the trough are limited by the diameter of the 10 mold which it must enter, the shape and size of the parts of the trough are somewhat fixed. The shape of the stream in the liners is deeper and narrower than is best suited for depositing the metal against the mold. The spout 12 is an uncooled extension of the trough with 15 the same limiting outside dimensions as the trough casing, but, because no space is required for the cooling chambers, greater latitude is permitted as to the shape of the channel. This channel is the same shape as the 20 channel of the liners, where the spout 12 contacts with the liners, but may broaden as shown in Fig. 8 and may also cut lower than is practical in the liners, as at 13—Fig. 1, in 25 order to decrease the distance through which the metal must fall from the spout to the mold. The spout 12 is attached to the casing in the sleeve beyond the cooling chambers by the pins 14 as shown in Fig. 5.

30 The spout 12 is designed to minimize the splashing in distributing the material in the mold. This is of considerable importance in the process of casting with a metal mold because the molten metal is subjected to a rapid 35 cooling. Consequently, if drops of the splashed metal fall upon a portion of the deposited metal that has cooled, or if it falls upon the surface of the mold not yet covered with metal, there will result excrescences or 40 defects in the casted object. The method of attachment and the shape of the spout channel prevent the lodgment of any portion of the molten metal in the spout or at its junction with the trough, and insures that all of the 45 metal is distributed in the mold. By making the spout separately detachable from the trough, replacements of the spout may be made in the event of its breakage or warpage.

It is not necessary that the lining be made of 50 one piece, for it may be composed of any desired number of sections, either coinciding with the slots 16 or terminating in multiples thereof. If a sectional lining is employed, the joinder of the sections may be by welding or 55 bolts.

Should the sections be welded together, as in Fig. 6, they may be of the general configuration of a continuous lining without slots. 60 In this case the slots might be formed by welding the sections at the bottom, as at 24, and extending the welding to the desired height, 17, on the side walls. Those portions of the ends that are not welded therefore 65 would form the sides of the slots, and the

depth and width of the slots would depend upon the extent of the welding.

Should it be desired to join the sections by means of bolts, there is shown in Fig. 7 a form for such a lining. In this case the sections are formed as in Fig. 6, with the exception that slight shoulder extensions 25 are provided at the bottom of the sections and the extent of which depend upon the size of slots desired. When the sections are then placed in alignment, the shoulders 25 will alone contact, the remainder of the section ends 26 forming the slots. There are recesses 27 in the base of the sections and apertures 28 corresponding to similar apertures in the other sections. A bolt 29 is placed in the aperture and fastened by means of a nut 30. The apertures and bolts may be rectangular to prevent rotation of the bolts. When properly adjusted the entire lining will be in alignment and ready for insertion in the casting. The bolts are of such length that the difference in expansion between the bolts and the lining will be practically negligible.

90 In Fig. 8 there is shown the channel of the spout. As before stated, the absence of cooling means in the spout permits an enlargement of its channel. It slants both downwardly and to the sides, pouring the metal in more nearly a flat sheet, and with less resulting splash. The channel of the trough lining at its termination is indicated at 31, from which the spout's channel slants away to its termination indicated by 32. It is to be observed that sufficient material is left between the channel and the casing to give the spout proper support. The dotted lines 2 and 4 represent the cooling systems mounted in each side of the trough. The pipes 6 and valves 7 for supplying the respective systems 95 with a cooling medium are also shown.

100 The lining shown in Fig. 9 may be adopted in lieu of the form shown in the other figures. Instead of having the slots merely at the top of the lining, there are also provided slots at the bottom as at 33. The connecting portions 34 are on the sides of the lining rather than at the base. As there is a greater variation in 105 expansion of the lining at the base than elsewhere, the presence of slots at that portion permits differential expansion without warping the lining.

110 In Fig. 10 there is shown a longitudinal sectional view of the lining with slots 33 extending upwardly from the bottom and opposite the slots 16. Under certain circumstances the slots may be in some arrangement other than that set forth in these figures.

115 Fig. 11 is a cross sectional view of the lining along the slots. The depth of the bond 34 in the channel may be varied, the most desirable place being that portion of the lining having the most nearly uniform temperature, for variation in the expansion of the 120 130

bond is to be avoided. A variation there will cause warpage, whereas variation along the slots will merely result in varying the width of the slots.

6 While Figs. 9, 10 and 11 indicate a continuous lining slotted, it is to be understood that it may be composed of sections suitably attached, as in the case of the lining with slots at only the top.

10 A modified trough casing may be employed, such as is shown in Fig. 12. It will be observed that the horizontal transverse axis is greater than the vertical. The trough may be of this shape, for there is less tendency for it to warp horizontally than to droop. The channel may therefore be increased to carry a greater quantity of metal with no increased danger of the trough scraping the mold. The same vertical clearance is permitted, while the horizontal clearance is decreased. The sides of the casing are partially cylindrical, while the base is flat as at 35.

25 Pipes are not employed in this form of trough, although under certain circumstances pipes may be substituted for the chambers 36 which are separated from the chambers 4 by the member 37. There are modified means 38 and 39 for maintaining the lining in the trough, while permitting longitudinal movement of the lining. It will be noted that in this type of trough a channel of rectangular cross section is desirable although the channel of the lining may be of substantially V-shape, as in the other type of trough.

35 As the molten metal passes through the trough channel both the lining and support member are heated. The lining is, of course, heated the most at the bottom where there is a more direct contact with the metal. As a consequence the lower portion expands more rapidly than the top, causing, in the absence of counteracting means, an upward curling. This invention prevents such a result, for the slots in the lining permit a greater expansion at the bottom than at the top. As the lining is fastened to the trough at only the end adjacent the spout, the expansion is in nowise hindered and the creeping that ensues is away from the spout.

40 Ordinarily the weight of the trough, and its lack of support for that portion extending within the mold, causes a sagging, as previously mentioned, seriously interfering with the efficient operation of the process, unless suitable preventive steps are taken. The tension in the upper portion and compression of the bottom of the trough, established by the sagging, are compensated for in this invention by the arrangement of the channel for the cooling medium. The difference in temperature of the cooling medium in the upper and lower conduits checks the expansion of the top and thus the sagging tendency of the trough is counteracted. The spout

serves to maintain the same rate and volume of flow as prevails in the trough, while causing the stream to change to a more desirable shape at the discharge end. The provision for quick and easy replacement of the spout curtails the loss of time ordinarily attendant in making repairs to such an apparatus.

70 One of the prime considerations in the art of centrifugal casting is assurance that the metal is distributed in the mold at a given rate and in a certain liquid state. The provisions of this invention, with the elimination of any possible obstruction and cause of hindering the flow of metal, insures a constant flow. As the fluidity of molten metal depends upon its temperature, a variation in the time required for the metal to pass from the ladle to the mold means a variance in its liquid state. Warpage of the lining or sag in the casing therefore would change the rate of flow and consequently vary the fluidity of the metal at its distribution in the mold. Protrusion or cavities that might effect a lodgment for the metal en route are, of course, to be avoided also, for even a temporary delay of part of the metal will mean a portion, at the time of distribution in the mold, varying from the fluidity of the rest of the metal, and a consequent premature cooling. This will cause flaws in the casted object. This invention, it is believed, overcomes the difficulties just enumerated. The non-warpage lining, non-sagging trough, and the spout provided all tend to insure a constant, uninterrupted, and even temperatured flow of metal.

75 80 85 90 95 100 105 110 115 120 125

It is perhaps needless to advert to the labor and money saving features of this invention. Suffice it to say that in such a process, with the large amount of capital invested, temporary delays in operation greatly increase the operating costs. The facility with which the parts of this invention may be substituted or replaced greatly decreases the amount of time lost in making repairs.

While I have shown and described the preferred embodiment of my invention, I wish it to be understood that I do not confine myself to the precise details of construction herein set forth, by way of illustration, as it is apparent that many changes and variations may be made therein, by those skilled in the art, without departing from the spirit of the invention, or exceeding the scope of the appended claims.

I claim:

1. A trough for pouring metal comprising a support member, and a continuous lining mounted therein, and secured thereto at one point only.
2. A lining for a metal conveying trough with transverse recesses at the top of said lining.
3. In a trough for pouring metal, a continuous lining having oppositely disposed

and axially perpendicular slots extending downwardly from the top of the lining to mediate points of the sides.

4. An end pouring trough in a rotary casting device comprising a casing, a lining, and means for maintaining a lining in the channel of the trough, while permitting independent expansion of the casing and lining.

5. In a trough for pouring hot liquids, a casting adapted to cool the top at a rate different from that at which the base is cooled.

6. A metal conveying trough for a rotary casting apparatus, comprising a support member with a conduit for a cooling medium at the top and another conduit for a cooling medium at the bottom, said conduits being in metallic contact with the support member, and adapted to cool the top of the trough at a greater rate than the base.

7. A support member for a trough comprising a casing, a chamber near the top for the receipt of a cooling fluid and the conduction thereof substantially the length of the support member, and a larger chamber in the bottom of the support member connected with said first mentioned chamber, and adapted to cool the top of the trough at a greater rate than the base.

8. An end pouring trough in a centrifugal casting apparatus comprising, a casing of partially cylindrical shape having a longitudinal channel, conduits for a cooling liquid in the top of the casing and larger conduits positioned in the bottom of the casing to receive the liquid after its flow through the first mentioned conduits.

9. A casing for a trough in a centrifugal casting apparatus comprising a partially cylindrical shell, members forming a longitudinal channel substantially the length of the shell adapted to receive a lining, protuberances on the said members for maintaining the lining in the channel, another channel substantially co-extensive with the first mentioned channel and positioned in the upper portion of the casing for the conveyance of a cooling liquid, a larger chamber in the bottom of the casing connected at one terminus with the second mentioned channel for conveying the liquid in the opposite direction to the flow in the second mentioned channel.

10. In a centrifugal casting apparatus, a trough comprising a shell of partially cylindrical shape, webs within the shell forming a longitudinal channel substantially the length of the shell and adapted to receive a lining, said webs having protuberances for fitting into corresponding recesses in the lining, lips on the shell for preventing vertical movement of the lining with respect to the trough, another channel substantially co-extensive with the first mentioned channel and formed in the upper portion of the casing, and a larger chamber in the bottom of the casing

connected at one terminus with the second mentioned channel and an outlet pipe at the opposite terminus of the chamber.

11. A pouring trough comprising a casing with arcuate sides and straight base, standards extending from the top of the sides to the intersection of the sides and base, horizontal members from the standards to the sides forming conduits in the upper side portions and chambers in the lower side portions, means for connecting the conduit and chamber, a lining for the channel formed by the standards and base and protuberances in the channel for maintaining the lining therein.

12. An end pouring trough comprising a support member, means to prevent sagging of the support member, and a non-warping lining mounted in the support member adapted to creep with respect to said support member.

13. In a centrifugal casting apparatus, a trough comprising a support member with conduits for a cooling medium positioned in its upper portion and chambers in its lower portion for receiving said cooling medium, a lining for said support member attached thereto at one point only, a chute and a spout attached thereto.

14. A trough in a rotary casting apparatus, comprising a partially cylindrical support member, independent conduits in the upper portion extending substantially the length thereof for conveying a cooling medium, independent longitudinal chambers positioned in the lower portion of the support member and connected to said first mentioned conduits, a lining secured to said support member at only one point having axially perpendicular slots extending downwardly from its upper edges, a chute for conveying molten metal to the trough, and a spout attached to the discharge end of the trough.

15. A trough for relative longitudinal movement with respect to a mold for centrifugal casting, comprising a casing of frusto-cylindrical shape, standards from the top of the casing forming a substantially V-shaped channel adapted to receive a lining, protuberances on the standards corresponding to recesses in the lining for retaining the latter in the channel, lips on the casing overhanging the lining, chambers for conducting a cooling liquid positioned near the intersections of the standards with the top of the casing, pipes near the discharge end of the trough connecting the said chambers with independent larger chambers in the lower portion of the trough, means for independently varying the temperatures of the media introduced to said upper chambers, an elongation of the casing shell; a lining for the channel formed by the standards having slots perpendicular to its longitudinal axis extending from the top of said lin-
